(57) **CLAIM**

The ornamental design for an enclosure for electronic equipment, as shown and described.

DESCRIPTION

FIG. 1 is a perspective view of the front of the electronic enclosure;

FIG. 2 is a left-side elevational view of the electronic enclosure;

FIG. 3 is a right-side elevational view of the electronic enclosure;

FIG. 4 is a top plan view of the electronic enclosure;

FIG. 5 is a bottom plan view of the electronic enclosure;

FIG. 6 is a front elevational view of the electronic enclosure;

FIG. 7 is a rear elevational view of the electronic enclosure; and,

FIG. 8 is a perspective view of the rear of the electronic enclosure.

The portions of the article depicted in the drawings with broken lines form no part of the claimed invention.
